UNITED STATES PATENT OFFICE

171,129

CALENDAR

James P. Goodson, Childress, Tex.

Application June 19, 1953, Serial No. 25,580

Term of patent 3½ years

(Cl. D74—5)

To all whom it may concern:

Be it known that I, James P. Goodson, a citizen of the United States, residing at Childress, in the county of Childress and State of Texas, have invented a new, original, and ornamental Design for a Calendar, of which the following is a specification; reference being had to the accompanying drawing, forming a part hereof.

Figure 1 is a front perspective view of a calendar showing my new design;

Figure 2 is a rear perspective view; and

Figure 3 is a top plan view thereof.

I claim:

The ornamental design for a calendar, as shown.

JAMES P. GOODSON.
